CARD INDEX

Charles E. Attwood, Chicago, Ill., assignor to
 Acme Visible Records, Inc., Chicago, Ill., a corporation of Delaware

Application November 12, 1940, Serial No. 365,249

3 Claims. (Cl. 129—16)

This invention relates to improvements in visible record systems of the class embodying a plurality of relatively small index cards arranged in chain-like groups and in overlapping relationship to expose marginal portions of the cards, and particularly to mounting and supporting means for such cards.

The use of index cards of the general type herein contemplated has been known in combination with various mounting or supporting means, such as, for example, metallic trays provided with fixed or detachable runways, the runways being rigid or substantially rigid, or with card holders swingably or hingedly mounted in frames, the individual index cards being interlocked with each other or directly engaged to the card holder by means of apertures, slots and other auxiliary aids.

It is an object of this invention to provide a truly flexible and detachable smooth runway or support for mounting a plurality of relatively small index cards provided with die-cut tabs in overlapping relationship with each other whereby a marginal edge portion is exposed, the runway or support being adapted to engage and interlock with an index card holder of a generally conventional type provided with a sheath at its lower marginal edge and hingedly mounted for use in a card holder or tray.

Another object is to provide a pocket card or holder having a transparent sheath adjacent its lower marginal edge to form a pocket for the reception of and to hold the lowermost card or strip in the chain and the base of the card runway, and having a longitudinal slot adjacent the upper marginal edge of the pocket card or holder for the reception of a tongue or lug extending from the head of the runway to form an interlock therewith.

Other objects relate to details of construction of the runway or support whereby it may be engaged in relatively fixed relationship with the pocket card or holder, to means for holding the cards in place thereon and preventing lateral movement thereof, together with other details of construction, arrangement of parts and economies thereof, which will be apparent from a consideration of the following specification and drawings, wherein:

Fig. 1 is a fragmentary front elevational view illustrating a record holder and a plurality of card holders embodying my invention.

Fig. 2 is a sectional view on the line 2—2 of Fig. 1.

Fig. 3 is a sectional view similar to Fig. 2, 55

illustrating the flexibility and method of operation of my novel component detachable card runway.

Fig. 4 is a fragmentary detail view of a hinged card holder and the slot thereof for engagement with the card runway.

Fig. 5 is an illustration of a die-cut index card employed with my invention.

Fig. 6 is a front elevational view of my flexible and detachable card support or runway.

Fig. 7 is a fragmentary front elevational view of the card runway and an index card in lowermost position thereon.

Fig. 8 is a fragmentary rear elevational view of the card runway and a plurality of index cards in lowermost position thereon.

Fig. 9 is a perspective fragmentary rearward view of my card runway with one index card in lowermost position thereon.

Referring to the drawings, 10 indicates a frame or support which may be utilized as a tray or drawer of a record cabinet, a leaf of a record book, for filing in vertical filing drawers, or a unit of the usual swingably mounted record or index stand. This frame 10 is generally constructed of metal and formed with a pair of opposed longitudinal flanges 11 beneath which are maintained flexible metallic hangers such as 12, to which card holders 13 are engaged by hinge means, such as 14. It will be understood, however, that various other means for hingedly mounting the card holders, well known in the art, may be employed with my invention. The card holder 13 is additionally provided with a sheath or pocket 15 embracing its lowermost marginal edge, the sheath being preferably of transparent material and secured to the card by means such as the staples 16.

The index cards 17 which are adapted to be utilized with my invention are of a conventional type, being die-cut to provide a pair of opposed tabs 18 which may be flexed and detachably engaged to support means therefor, in overlapping engagement with each other whereby a marginal edge portion of the cards remains exposed for the reception of indicia.

The card support means in accordance with my invention comprises a runway element 19, formed of smooth flexible material, such as for example Celluloid which will not appreciably deform on repeated use although it may have a relatively thin yet sufficiently strong body for the supporting use herein contemplated. The runway 19 is provided with a pair of laterally extending shoulders 20 adjacent the head portion

thereof, and a pair of laterally extending shoulders 21 at the base thereof. One function of the shoulders 20 and 21 is to provide stop or limiting means for sliding movement longitudinally thereof of index cards 17 engaged thereto, the base shoulders 21 additionally serving maintain the lowermost engaged index card at a position whereby its lowermost edge substantially coincides with the lowermost edge of the runway 19, and for cooperative use therewith, as will be hereinafter more fully described. The head portion of the runway 19 is provided with a tongue or lug 22 of appreciable width extending between the shoulders 20.

The card holder 13 is provided with one or more longitudinally extending slots 23 adjacent the upper marginal edge thereof, each slot 23 being adapted to receive a runway tongue 22, the movement of the tongue through the slot being limited by the length of the tongue and the laterally extending shoulder portions 20 thereat. The length of the runway 19 is such that the distance between the base of the tongue 22 and the lower terminal edge of the element is substantially equal to the distance between the slot 23 and the fold of the sheath 15. It will be understood that the card holder 13 may be provided with a suitable number of spaced apart slots 23, dependent on the width of the card holder or width of the index cards 17. Thus as illustrated in Fig. 1, two slots are provided so that two elements 19 may be engaged, the sheath 15 being common to both.

As hereinbefore stated, the relationship of the height of the base shoulders 21 to an index card 17, or the die-cut thereof, is such that the lower marginal edge of the lowermost card mounted on runway 19 substantially coincides with the lower edge of runway 19, as best illustrated in Figs. 7, 8 and 9. Thus when a runway 19 having a chain of cards 17 thereon is to be mounted on a card holder 13, the lower marginal edge of a lowermost index card together with the base of the runway is inserted within sheath 15, and thereafter the freely flexible runway 19 with its chain of cards 17 is flexed, as illustrated in Fig. 3, and the wide lug or tongue 22 at the head thereof is inserted in slot 23. Thereafter the resultant return to normal length of the runway 19 extends it between the fold of the sheath 15 and the slot 23 whereat it is stopped by the shoulders 20. This together with the engagement of the base of the runway 19 and the greater width of the lowermost carried index card also engaged in the sheath 19, securely holds the loaded runway in normal useful position on the card holder, and particularly tends to prevent any sidewise movement of the cards or pivotal movement of the runway.

It will thus be apparent that I have provided simple, economical, novel and useful means for readily assembling comparatively small index cards or strips of the type adapted to be arranged in overlapping chain-like formation, comprising a smooth runway or support for ease in assembly, which is detachable for ready interchange, correction, assembly and the like, and which is freely flexible without tendency to become distorted, the runway by reason of its free flexibility and other details of construction being adapted for firm engagement with a card holder of a general type used in visible index systems provided with a pocket sheath.

15 I claim as my invention:

1. In a visible index record filing means, a card holder having a sheath located along substantially its entire lower marginal edge, the upper portion of said card holder being provided with one or more intermediately located slots adjacent to and parallel with the upper edge thereof, and a freely flexible runway for supporting index cards, said runway being of a length substantially equal to the top to bottom length of said card holder, the upper portion of said runway being provided with a centrally located tab adapted to be positioned in said slot and having laterally projecting card abutting shoulder portions of greater end-to-end width than the width of said runway extending therefrom, the lower portion of said runway also being provided with card abutting shoulder portions of substantially the same width as the said upper shoulder portions, said lower shoulder portions being adapted for detachable retention in said sheath.

2. In a visible index record filing means, a runway comprising a freely flexible Celluloid strip having upper and lower opposed shoulder tabs extending laterally therefrom, the upper portion of said strip being provided with a tab centrally located between said upper shoulders and extending perpendicularly thereto, and the lower portion of said strip being substantially straight from end to end of said lower shoulders.

3. In a visible index record filing means, a runway comprising a freely flexible elongated strip having upper and lower opposed shoulder tabs extending laterally therefrom and greater in end-to-end width than the width of said strip, the upper edge portion of said strip being provided with a tab centrally located between said upper shoulders and extending perpendicularly thereto, and the lower portion of said strip being substantially straight from end to end of said lower shoulders, the lateral distance between the ends of the upper and lower portions, respectively, being substantially the same.

CHARLES E. ATTWOOD.
